UNITED STATES PATENT OFFICE

GEORGE H. MAGRATH, OF WHITINSVILLE, MASSACHUSETTS

BOBBIN CLUTCH

Application filed August 26, 1930. Serial No. 477,811.

This invention relates to an improvement in bobbin clutches for rotatable spindles in which the clutching members are provided to fit within the base of the bobbin and to expand therein, thus to maintain the bobbin in position during the spinning or other operation. More particularly this invention embodies an improved spring element which is adapted to be used in bobbin clutches of the type shown in my copending application Serial No. 295,158, filed July 25, 1928, now Patent No. 1,820,574, issued August 25, 1931, as well as in various other types well known in the art.

It is the object of this invention to provide a spring element which is simple and economical to manufacture, which is efficient and durable in use, and which is generally superior to those heretofore used in bobbin clutches. Further objects and advantages will be apparent as attributes of the construction and design hereinafter to be set forth and described.

This invention provides a spring element which comprises spring metal wire so mounted as to afford a plurality of upwardly extending, symmetrically disposed, circumferentially spaced resilient fingers. A particularly desirous feature in the manufacture of such a spring is that there is no necessity for heat treatment after shaping. Dispensing with this relatively expensive and time-consuming operation not only produces a less expensive structure, but also one which is tenacious and durable in contradistinction to the spring elements now or heretofore used which require heat treatment, which results in the production of a brittle structure not adapted to stand the stress and strain to which such elements are subjected.

As the general construction and operation of rotatable spindles with expandible clutching members are well known and familiar to those skilled in the art, it will only be necessary here to illustrate and describe the parts directly concerned with the present invention.

In the drawing:

Fig. 1 is a vertical cross section of a clutch mechanism;

Fig. 2 is a transverse cross section taken on line 2—2 of Fig. 1;

Fig. 3 is a plan view and elevation of the spring; and

Fig. 4 is a plan view of a collar used in one embodiment of the invention.

The particular embodiment of the invention chosen for the purpose of illustration comprises an ordinary blade 1 and whirl 2 fixedly mounted thereon by a pressed fit, the whirl 2 having a hub 3 from which projects a neck or sleeve 4 and a flange 5 with an annular recess 6 therebetween. The case 7 mounted on the blade 1 in opposition to the hub 3 has four radial slots extending longitudinally from one end throughout the major portion of the length of the case 7 leaving therebetween finger portions 8 which project into the annular recess 6. Disposed in the aforesaid slots are the contact pieces 9 of the clutching members 11, having their upper ends lipped to engage inside the case 7, as shown in Fig. 1, and having their lower ends terminating in outwardly projecting feet 10 extending into and resting on the bottom of the annular recess 6. The clutching members 11 are preferably held in position by a ring 12 forced in the annular recess 6 above the feet 10.

The spring element 13, shown in Fig. 3, is a one-piece structure formed from a blank of spring steel wire. The blank is bent or shaped to define annular base sectors 14, upwardly extending, symmetrically disposed, circumferentially spaced resilient fingers 15, the upper portions of which have outwardly flaring tips 16. Preferably the ends 17 of the spring are welded together.

Seated on the neck 4 is the spring 13 with its annular base sectors surrounding the blade 1, and the flared tips 16 of the projecting fingers 15 engaging the clutching members 11 near their upper ends, as shown in Fig. 1. The width of the fingers 15 is equal to or preferably slightly less than the width of the contact pieces 9. The collar 18 with laterally-projecting tabs 19 is fitted on the blade 1 with its tabs 19 extending between the fingers 15 of the spring 13 and their under surfaces in pressing contact with the 100

base portions 14 of the spring, as shown in Fig. 1. The collar is held in this position preferably by means of a pressed fit on the blade 1, or it may be effectively so held by a 5 pressed fit resulting from the contact of the ends of the tabs 19 with the lower interior walls of the finger portions 8 of the case 7. Either way the relative positions of the fingers 15 of the spring, the clutching members 10 11, and the case fingers 8 is maintained.

In assembling the parts the whirl 2 is preferably applied to the blade 1 first; the spring 14 is dropped on the blade and then the collar 18 is pressed on the blade in close relation to the neck. The case 7 is pressed partially on the blade and the clutching members 11 are inserted in the radial slots between the fingers 8 of the case and while being so held (by a temporary ring or equivalent means) the case is pressed into position with its fingers 8 extending into the annular recess 6. The ring 12 which holds the feet 10 of the clutching members 11 is then pressed into place.

25. From the foregoing it will be evident that the spring is held in position by the collar, which is maintained in fixed relation to the blade and consequently the spring fingers 15 through the medium of the clutching members 11 will yieldingly engage the bobbin to hold it in position.

30. It should be understood that the present disclosure is for the purpose of illustration only and that this invention includes all 35 modifications and equivalents which fall within the scope of the appended claims.

I claim:

40. 1. Apparatus of the character described comprising a blade, a whirl secured to the blade, the whirl having a hub provided with a neck fitting around the blade and an annular recess surrounding the neck, a case concentric the blade and secured at its upper end thereto and having a plurality of vertical slots, a plurality of clutching members seated at their lower ends in said recess with their contact segments disposed in the vertical slots of the case, a spring comprising a piece of resilient wire shaped to define an 45 annular base and a plurality of upwardly extending resilient fingers, said spring being concentric the blade within the case and having its fingers engaging said contact segments, and means for securing said spring in 50 a fixed relation to the clutching members.

55. 2. A bobbin clutch comprising a blade, a whirl secured to the blade, the whirl having a hub provided with a neck fitting around the blade and an annular recess surrounding the neck, a case concentric the blade and secured at its upper end thereto and having a plurality of symmetrically disposed, vertical slots, a plurality of clutching members seated at their lower ends in said recess with 60 their contact segments disposed in the verti-

cal slots of the case, and a spring comprising a piece of resilient wire shaped to define an annular base and a plurality of upwardly extending resilient fingers, said spring being concentric the blade within the case and having its fingers engaging said contact segments. 70

3. A bobbin clutch comprising a blade, a whirl secured to the blade, the whirl having a hub provided with a neck fitting around the blade and an annular recess surrounding the neck, a case concentric the blade and secured at its upper end thereto and having a plurality of symmetrically disposed, vertical slots, a plurality of clutching members seated at their lower ends in said recess with their contact segments disposed in the vertical slots of the case, a spring comprising a piece of resilient wire shaped to define an annular base and a plurality of upwardly extending resilient fingers, said spring being concentric the blade within the case and having its fingers engaging the contact segments, and an annular collar concentric the blade and having a plurality of radially projecting tabs 80 engaging the base portions of the spring to hold the same in fixed position. 85

Signed by me at Boston, Massachusetts this 20th day of August, 1930.
